UNITED STATES PATENT OFFICE.

CHARLES M. ROBINSON, OF TOLEDO, OHIO.

DESIGN FOR A COOKER.

SPECIFICATION forming part of Design No. 35,479, dated December 24, 1901.

Application filed November 8, 1901. Serial No. 81,630. Term of patent 7 years.

To all whom it may concern:

Be it known that I, CHARLES M. ROBINSON, residing at Toledo, in the county of Lucas and State of Ohio, a citizen of the United States, have invented and produced a certain new and original Design for a Cooker, of which the following is a specification, reference being had therein to the accompanying drawings, in which the figure is a perspective view of the cooker.

A is a rectangular body having a substantially square top and of greater height than width. The top B has a raised circular boss C, with the concentric bead D. Upon one side of the body is a cylindrical extension E, having its axis perpendicular to the plane of the side. F is a projection from the body below and in vertical line with said cylindrical extension, and G is a rounded connecting-bar

between said upper and lower projections. 20
The adjacent side of the body is provided with raised rectangular panels H.

The leading feature of the design consists in the rectangular body having the cylindrical extension from one of the vertical faces thereof, a projection below and in vertical line with said cylindrical projection and a rounded bar connecting the two. 25

What I claim as my invention is—

The design for a cooker, substantially as 30
herein shown and described.

In testimony whereof I affix my signature in presence of two witnesses.

CHARLES M. ROBINSON.

Witnesses:
